Frank Adams

UNITED STATES PATENT OFFICE.

JOSEPH BETHENOD, OF PARIS, FRANCE.

CALLING SYSTEM FOR RADIOSIGNALING.

Application filed August 2, 1921. Serial No. 489,304.

(GRANTED UNDER THE PROVISIONS OF THE ACT OF MARCH 3, 1921, 41 STAT. L., 1313.)

To all whom it may concern:

Be it known that I, JOSEPH BETHENOD, a citizen of France, and resident of Paris, France, have invented certain new and useful Improvements in Calling Systems for Radiosignaling (for which I have filed applications in France Dec. 12, 1919, and Dec. 23, 1919), of which the following is a specification accompanied by drawings.

10 Calling systems for wireless telegraphy or telephony must be as sensitive as possible to the call which is sent out and at the same time it must not respond to other transmissions and particularly to atmospherics.

15 In accordance with the present invention, these two requirements are realized as follows:

(1) An energy integrating device is used, and is actuated only in case the transmission 20 is of a sufficiently long duration. In this manner, the average power necessary for the operation is reduced and the device is not responsive to short impulses and to atmospherics that have a periodic character.

25 (2) A selecting and amplifying circuit is used.

Assuming that continuous waves are transmitted, the following arrangement is described for the purpose of illustrating the 30 invention.

Fig. 1 is a diagram of connections of the preferred form of my invention.

Fig. 2 shows a modification of my invention in which a tuning fork is set into vibration by the received oscillations.

Fig. 3 shows an alternative arrangement of the tuning fork, and

Fig. 4 shows an arrangement comprising a gas thermometer.

40 In accordance with the diagram of Fig. 1, the call signal is received and amplified by means of a tube amplifier 1, preferably a resonance amplifier; a local heterodyne 2 (or amplifier in autodyne arrangement) generates beats which are detected. The current of musical frequency thus obtained, actuates a resonance transformer 3, the secondary of which heats a thermoelectric element 4. The continuous current generated

45 by this element, actuates a contact galvanometer 5. Preferably, this galvanometer is of the ballistic type having a long period 50

and high damping. When the contact is closed, a relay 6 is actuated. This relay is not provided with a retractile spring. The 55 relay actuates a bell or any other indicating apparatus 7 until the operator returns the relay to its normal position.

If required, this arrangement may be considerably simplified. The element 4 may be 60 heated by the frequency current received by the antenna and suitably amplified. In this case no detecting is necessary.

The characteristic principle of this modification is the combined use of a thermoelectric element and a contact galvanometer 65 having a long period, the long period system having the advantage that it integrates the energy and does not respond to disturbances 70 of short duration.

In accordance with another modification, the assembly 4 and 5 may be replaced by an ordinary Riess thermometer, or preferably, may be arranged in the following manner as shown by Fig. 4: A horizontal capillary tube 21 in which a more or less long mercury indicator 22 moves, interconnects two bulbs 23 filled with a suitable gas, such as hydrogen, nitrogen, air. Each of these bulbs contains a filament 24. One or the other of 80 these filaments may be traversed by a weak current. The sensitiveness of the arrangement is the greater, the weaker the pressure in the two bulbs. It is independent of the atmospheric pressure, but depends on the 85 temperature of the assembly. Partially evacuated bulbs may also be used for this purpose. The assembly must be enclosed with a heat insulating casing 25. Under the control of the heat that is released, the indicator is actuated and closes the signalling circuit by means of a suitably provided contact, etc.

In accordance with the modification of Fig. 2, the low frequency current generated 90 by the receiving apparatus (current that cannot be rectified) actuates a tuning-fork mounted on a resonance box, the musical tone of the vibrating system corresponding to the frequency of the receiving current 100 (simple or double variant depending on whether or not the tuning fork is polarized). Due to the mass to be vibrated, this arrangement is in the class of energy integrators.

At the same time, the arrangement has selecting qualities and responds only to transmissions of sufficient length. In this manner, the atmospherics are rendered harmless.

5 In the drawing, Fig. 2 shows an illustration of a circuit arrangement for such apparatus. In this figure, 1 represents the receiving box which may comprise any useful amplifying devices, such as a heterodyne or 10 autodyne source if continuous waves are to be received. The current of suitably tuned musical frequency leaving this box, causes the vibration of a tuning fork 12, whereby a tone corresponding to this frequency is 15 produced (tone of double frequency if the current is not rectified). The tuning fork is mounted on a resonance box 13 and is controlled, e. g., through the agency of an electromagnet 14. This magnet is shown as a 20 simple coil having a laminated metal core, but obviously it may have various other forms, such as suitably arranged multiple coils on the two sides of each prong, etc. In accordance with the arrangement shown in 25 Fig. 3, the magnet may have the form of a solenoid completely surrounding the two prongs of a narrow tuning-fork 12, these prongs being of nonmagnetized magnetic metal. Furthermore, it may be advisable to 30 add a device (not shown) adapted to close an electrical circuit when the prongs of the tuning fork attain the maximum amplitude, whereupon a permanent indicator will be actuated. This indicator may be visual, and 35 serves to control the purely acoustic call. Means may be provided in the form of a horn, etc., for reinforcing the vibrating assembly.

Having described my invention, what I claim is:

1. In a calling system for wireless signaling, the combination of receiving circuits, and indicating means for received currents, said indicating means comprising a ballistic galvanometer having considerable inertia whereby it is unresponsive to short impulses having a time duration less than that of a dash in the Morse code. 40
2. In a calling system for wireless signaling, the combination of receiving circuits, a thermoelectric element connected to the receiving circuits and indicating means for received currents, said indicating means having considerable inertia whereby it is unresponsive to short impulses having a time duration less than that of a dash in the Morse code. 45
3. In a calling system for wireless signaling, the combination of receiving circuits, a thermoelectric element connected to the receiving circuits and a damped galvanometer connected to the thermoelectric element, said system being unresponsive to impulses having a time duration less than that of a dash in the Morse code. 50
4. In a calling system for wireless signaling, the combination of receiving circuits, a thermoelectric element connected to the receiving circuits, a damped galvanometer connected to the thermoelectric element and a relay cooperating with the galvanometer, said system being unresponsive to impulses having a time duration less than that of a dash in the Morse code. 55

JOSEPH BETHENOD.
